(57) **CLAIM**

The ornamental design for a screen for electronic cigarette, as shown and described.

DESCRIPTION

FIG. 1 is a perspective view of the screen for electronic cigarette in accordance with the present design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines and the unshaded areas adjacent to them depict portions of the screen for electronic cigarette that form no part of the claimed design.

1 Claim, 7 Drawing Sheets
